(57) **CLAIM**

The ornamental design for the instant-read thermometer, as shown and described.

DESCRIPTION

FIG. 1 shows a perspective view of the front side of the instant-read thermometer.

FIG. 2 shows a front view of the instant-read thermometer.

FIG. 3 shows a back view of the instant-read thermometer.

FIG. 4 shows a left side view of the instant-read thermometer.

FIG. 5 shows a right side view of the instant-read thermometer.

FIG. 6 shows a top view of the instant-read thermometer; and,

FIG. 7 shows a bottom view of the instant-read thermometer. The broken lines are included for the purpose of illustrating portions of the instant-read thermometer and form no part of the claimed design.

The break lines in the drawings indicate that the appearance of any portion of the instant-read thermometer between the break lines forms no part of the claimed design.
